US0D1006657S

(12) **United States Design Patent** (10) Patent No.: **US D1,006,657 S**
(45) Date of Patent: ** Dec. 5, 2023

(54) **KINETIC MEASURING INSTRUMENT FOR HUMAN MOTION ANALYSIS**

(71) Applicant: **SMART2MOVE AG**, Allschwil (CH)

(72) Inventors: **Gregory Lebrat**, Blotzheim (CH);
Ronald Gröflin, Binningen (CH)

(**) Term: **15 Years**

(21) Appl. No.: **35/515,259**

(22) Filed: **Sep. 17, 2022**

(80) **Hague Agreement Data**

Int. Filing Date: **Sep. 17, 2022**

Int. Reg. No.: **DM/223552**

Int. Reg. Date: **Sep. 17, 2022**

Int. Reg. Pub. Date: **Sep. 30, 2022**

(57) **CLAIM**

The ornamental design for a kinetic measuring instrument for human motion analysis, as shown and described.

DESCRIPTION

1. Kinetic measuring instrument for human motion analysis

1.1 : Perspective view (front,top, left)

1.2 : Perspective view (front, top, right)

1.3 : Front

1.4 : Back

1.5 : Left

1.6 : Right

1.7 : Top

1.8 : Bottom

1 Claim, 8 Drawing Sheets
